BUILDER-MOTION.

1,247,880.

Specification of Letters Patent. Patented Nov. 27, 1917.

Application filed April 22, 1915. Serial No. 23,238.

To all whom it may concern:

Be it known that I, ALONZO E. RHOADES, a citizen of the United States, residing at Hopedale, in the county of Worcester and State of Massachusetts, have invented an Improvement in Builder-Motions, of which the following description, in connection with the accompanying drawings, is a specification, like letters on the drawings representing like parts.

The invention to be hereinafter described relates to spinning apparatus, and more particularly to the means for placing upon a carrier or bobbin preliminary windings, and thereafter the main or service windings. The filling carriers or bobbins thus wound are used in automatic filling replenishing looms of the so-called "feeler type", and in certain forms of such looms the preliminary windings or bunch coöperate with the feeler, when the filling has become practically exhausted, to initiate filling replenishment. The preliminary windings or bunch in such cases affords sufficient filling upon the carrier or bobbin to insure the continuity of the filling laid in the shed after call for filling replenishment.

A number of patents have been granted for different characters of apparatus to insure the formation of a bunch upon the bobbin, and to define the form of the bunch in order that the filling may be withdrawn from the carrier or bobbin without danger of breaking. One form of means to this end is shown and described in Patent No. 913,164, dated February 23, 1909, wherein certain means is disclosed for increasing the "gain" of the traverse during the preliminary winding, in order to impart a greater taper to the bunch, so that the yarn will not catch onto the inner end thereof during the weaving operation. Other patents have also been granted to me for mechanisms having for their general purposes, modifications in the form and character of the bunch produced.

When replenishment is effected, in a loom of the feeler type, that yarn or thread which remains upon the abandoned filling carrier or bobbin becomes waste; consequently, the less yarn or thread that shall remain upon

the abandoned filling carrier after the replenishing operation, consistent with a proper continuity of the thread laid in the shed, the less will be the resulting waste. Feeler looms have therefore been provided with feeler mechanisms which, when the filling had become exhausted to the predetermined extent, would enter a slot or opening in the carrier or bobbin and initiate filling replenishment.

In order that the feeler and slotted carrier or bobbin shall effectively coöperate to effect filling replenishment, it is necessary that the slot in the carrier or bobbin shall be exposed to the entrance of the feeler, and that there shall yet remain upon the carrier or bobbin sufficient yarn or thread to insure the continuity of the filling laid in the shed.

The aims and purposes of the present invention are, therefore, to provide means whereby a filling carrier or bobbin may have wound thereon preliminary windings of filling beyond one end of the slot in the carrier or bobbin to insure continuity of the filling laid in the shed after the service windings have been unwound to properly present the slot in the carrier or bobbin to the free entrance of the feeler. A good practical form of the invention is hereinafter described in connection with the accompanying drawings, but it will be understood, of course, that various details may be changed within the true scope of the invention as pointed out by the claims.

In the drawings:—

Figure 1 is a plan view showing the means interposed between the rocker arm and the builder motion for modifying the action of the builder motion during the formation of the preliminary windings, and for thereafter imparting to the ring-rail its regular traverse;

Fig. 2 is a side view of the parts shown in Fig. 1, with some of the features shown broken away, and in section, the rocker arm and ring-rail being indicated by dotted lines.

Fig. 3 shows a filling carrier or bobbin provided with the character of windings contemplated by the present invention.

The frame 1 of the machine may be of any

usual character common to ring spinning machines, for instance, and appropriate for supporting the operating parts. Suitably associated with the frame 1 is the ring-rail 2, shown by dotted lines in Fig. 2, and carrying a series of spinning rings 3 of usual character. Mounted on the bracket 4 projecting from the frame 1, is the rocker arm 5 having the usual quadrant 6 to which is secured one end of a flexible connection 7, as at 8, the other end of said flexible connection 7 being connected to the slide, as will herein-after more fully appear.

The rocker arm 5 is preferably mounted on the cross shaft 9 and secured thereto, said shaft 9 being supported by brackets 4. Extending from the shaft 9 and secured thereto, are the lifter arms 10 which underlie the feet 11 on the rods 12 upon which the ring-rail 2 is mounted, the construction being such that upon rocking movement of the rocker arm 5, the ring-rail 2 will be raised and lowered in a manner well understood by those skilled in the art. It will also be understood that there may be a series of rods 12 extending from the ring-rail 2 and operated by suitable lifter arms 10 operatively connected for movement in unison, all as usual.

The builder motion may comprise the usual builder arm 13 and its associated part, such as the pick-wheel 14, and extending between the builder motion, which may be of usual character and construction, is the flexible connection 15 which passes around suitable guide pulleys 16 and 17, Fig. 2. A suitable form of builder motion is shown by the patent to Rhoades, No. 913,164, February 23, 1909, and No. 941,650, November 30, 1909.

Secured to the main frame 1 is a support for the operating parts of the means disposed between the builder motion and the rocker arm for modifying the action of the builder motion. This support may be of any appropriate form or character, but as shown in the drawings, it comprises the longitudinally-extending side bars 18 secured in parallel relation by means of the bolts 19 at either end, and the spacing blocks 20. The side bars 18 are connected by brackets 21 to one of the longitudinal girders of the main frame as by means of the clamps 22, Fig. 1, the construction being such that the support constituted by the side bars 18 will be sustained by the main frame preferably between the side members thereof.

Mounted between the side bars 18 of the support, is the slide 23 having portions 24 running in suitable guideways in said side bars. Projecting from one end portion of the slide 23 is a hook 25 to which is connected one end of the flexible connection 7, hereinbefore described. From the construction thus far described, it will be apparent

that reciprocating motion of the slide 23 will be imparted to the rocker arm through the quadrant 6 and the ring-rail will consequently be given the desired rising and falling movement.

The slide 23 is provided with a perforation 26 through which passes the lever 27 pivotally connected to the slide at 28. The upper end portion of the lever 27 is connected to a rod 29 having a bent end 30 engaged with the connection 15 leading to the builder motion. The opposite end of the lever 27 is connected by a chain or like flexible part 31 to a hook 32 formed in the end 30 of the rod 29, the construction being such that as the builder arm of the builder motion rises and lets back the connection 15, the lever 27, if permitted, will move bodily with the slide 23 as the rocker arm 5 draws the slide to the right, Fig. 2, it being understood that the shaft 9 is provided with the usual lifter weight, not shown, for lifting the ring-rail 2.

Pivotedly mounted at 33 on the support or side bar 18, is the latch-carrying arm 34 weighted at 35 to normally lift its opposite end portion 36 for a purpose that will herein-after more fully appear. Pivotedly mounted at 37 on the latch-carrying arm 34 is the latch 38, the end 39 of which is provided with a seat, Fig. 2, adapted to engage at certain times, a corresponding or complementary part 40 on the lower arm of the lever 27, in order to modify the traverse imparted by the builder motion during the preliminary windings. Since the lever 27 thus acts to modify the traverse imparted by the builder motion, it may, for identification, be herein termed the "traverse modifier."

The latch 38 is provided with a weight 41 at one end, which acts normally to hold the end 39 thereof in raised position, a stop 42 on the latch-carrying arm serving to limit the upward movement of the end 39 of the latch.

Mounted in suitable bearings 43 sustained by one of the side bars 18, is the ratchet cam 44, a part of whose periphery is provided with a series of ratchet teeth 45. The ratchet cam 44 carries a cam portion 46 having an abrupt drop 47 for a purpose that will presently appear. Mounted to rotate with the ratchet cam 44 is the pulley 48 about which passes a chain or other flexible connection 49 carrying a weight 50, the construction being such that the weight 50 normally acts upon the pulley 48 and perforce, upon the ratchet cam 44 to rotate them in opposition to the ratchet teeth 45, viewing Fig. 2. Adjustably mounted upon the supporting frame and preferably upon one of the side bars 18, is an adjustable stop 51 having an end portion 52 adapted to engage the end tooth of the ratchet cam when said

ratchet cam is freed to rotative movement under the demand of the weight 50. The adjustable stop 51 may be adjustably secured to the supporting frame in any appropriate manner, and as shown, it is provided with a slot 53 through which pass suitable securing means such as the bolts 54, the construction being such that upon loosening the bolts 54 the stop 51 may be adjusted to different positions for determining the number of layers that may be laid in the preliminary windings, as will hereinafter more fully appear.

Pivottally mounted at 55 is a retaining pawl 56, the end 57 of which is adapted to engage the ratchet teeth 45 and hold the cam 44 from rotation under the demands of the weight 50. Projecting from the pawl 56 is a tail-piece 58 having a side projecting inclined cam portion 59 which at times is adapted to be engaged by a projection such as the roll 60 carried by the traverse modifier 27, the construction being such that so long as the pawl 56 is not lifted by the roll 60 on the traverse modifier, it will continue to hold the ratchet cam from rotative movement under the demands of the weight 50, as will be obvious.

Secured to the slide 23 by any appropriate form of securing means, such as the bolts 61, is the operating pawl carrier 62 having pivoted to its upwardly-projecting end portion at 63, the pawl 64, the end of which is adapted to engage the ratchet teeth 45. The swinging movement of the pawl about its mounting 63 is limited by a knife-joint or stop 65 so that when the pawl 64 is moved to the right out of engagement with the ratchet cam member, it will not drop too low or out of operative relation thereto.

It is a purpose of the present invention to lay the preliminary windings or bunch upon the bobbin by a sufficient number of traverses beyond one end of the slot 68 in the bobbin to insure continuity of the filling laid in the shed after the feeler in the loom has indicated substantial exhaustion of filling; and it is a further important feature of the invention that when substantial exhaustion of filling has been reached, the slot 68 in the bobbin will be entirely uncovered to insure entrance of the feeler on a detecting beat and consequent initiation of filling replenishment. To these ends, the preliminary windings 66 are laid upon the bobbin or carrier with a short traverse, and short gain, and upon their completion the service traverse and service gain are at once resumed, to thereby cover by the first service winding, the feeler slot 68 in the carrier or bobbin. This service traverse and service gain then continue.

In order that the base portion of the wound bobbin shall conform to the requirements of the builder motion, the shortening of the traverse and gain in laying the pre-

liminary windings is confined to that movement of the traverse toward the tip of the bobbin, the consequence being that upon the completion of the preliminary windings the service windings may be at once resumed under full traverse and gain without distorting the form and character of the wound bobbin at the base thereof.

Having determined the number of layers to be laid by the preliminary windings to form the bunch, the stop 51 is appropriately adjusted to engage the end tooth of the ratchet 45 in such position that the requisite number of teeth will appear between the stop and the holding pawl 56. The end 36 of the latch carrier 34 will rest upon the cam 46 and the end 39 of the latch 38 will be raised into the path of the projection 40 of the traverse modifier. At the commencement of the winding operation the slide 23 will be at the left, and as the slide is let back by the builder motion on the first upward movement, the projection 40 of the traverse modifier will engage the end 39 of the latch 38 and further movement of the slide to the right, Fig. 2, will cause the traverse modifier 27 to turn upon its pivotal mounting 28, thereby shortening the traverse and gain in traverse proportionately during movement of the slide to the right. This movement of the slide to the right, Fig. 2, during the preliminary windings is not sufficient to cause the roll 60 on the traverse modifier to engage the incline 59 of the retaining pawl 56, so the latter remains in engaging portion with respect to the ratchet 45. As the slide moves to the right it carries the operating pawl 64, which on the return movement of the slide to the left under the control of the usual builder arm, engages the ratchet 45 and turns the ratchet cam 44 the distance of one or two teeth according to the adjustment of the pawl. The holding pawl 56 engages the ratchet in the new position and holds the ratchet cam 46 from movement responsive to the weight, as the slide makes its subsequent movement to the right. This action of the parts will continue until the raised portion of the cam 46 passes beyond the end 36 of the latch carrier, which will occur when the predetermined number of traverses have been made to form the bunch, whereupon the end 36 of the latch carrier will drop into the recess 47 of the cam and the end 39 of the latch will drop below or out of the path of movement of the projection 40 of the traverse modifier with the result that on the next movement of the slide to the right, the projection 40 will fail to engage the end 39 of the latch and full service traverse and gain will be given the ring rail.

When the carriers or bobbins have been partially filled or wound, the movement of the slide 23 to the right is sufficient to cause

- a projection 69 extending downward from the slide 23 to engage a cam piece 70 projecting from the side of the latch-carrying arm 34, thereby moving the end 36 of the 5 latch-carrying arm out of the depressed portion of the cam 46, and simultaneously or about this time, the roll 60 on the traverse modifier 27 engages the inclined cam piece 59 on the tail portion 58 of the pawl 56, 10 and disengages the retaining pawl from the ratchet, whereupon the weight 50 asserts itself and turns the ratchet cam 44 clockwise, Fig. 2, until the end tooth of the series 45 engages the end 52 of the adjustable 15 stop, it being understood that the operating pawl 64 at this time has been moved by the slide 23 to the right out of engagement with the ratchet tooth. When the filling carriers or bobbins have been completed and upon 20 "winding back," the slide 23 is moved to the left, whereupon the operating pawl 64 engages the ratchet teeth 45 and in the present instance of the invention moves the parts into the position indicated in Fig. 2, ready 25 to commence or start the initial windings.

In the construction described, the adjustment of the stop 52 is such as to cause two traverses only of the preliminary windings, that is, one up and one down, before passing directly into the service windings; but if it should be desired to increase the number of layers in the preliminary windings, it is necessary only to adjust the stop 51 so that an increased number of ratchet teeth 35 45 shall be positioned to the right of the operating pawl 64 when the latter moves the ratchet cam to starting position in winding back.

From the construction described, it will 40 be apparent that means are herein provided between the ring-rail and builder motion to lay the yarn upon a carrier or bobbin with a service length of traverse and a service gain in traverse as prescribed by the builder 45 motion, and that such service length of traverse and service gain in traverse are modified proportionally during the formation of the preliminary windings, such proportional modification being confined to that 50 movement of the traverse toward the tip end of the bobbin.

Modifications and changes may be made in some of the details of the illustrated embodiment of the invention, but those described have been found to be of good practical form, and to contain novel characteristics in themselves.

What is claimed is:—

1. In a machine of the character described, the combination of the ring-rail, a builder motion for imparting movement to the ring-rail to lay the yarn upon a bobbin with a service length of traverse and gain in traverse, a slide, a lever pivoted between its 60 end to the slide, means for connecting opposite ends of the lever with the builder motion, a latch carrier, a cam for controlling the latch carrier, a latch pivotally mounted on the latch carrier and having a seat adapted to repeatedly engage the said lever as the 65 slide is reciprocated, and means for operating the cam as the slide is reciprocated to cause the latch to be moved into an inoperative position relative to the said lever.

2. In a machine of the character described, 70 the combination of the ring-rail, a building motion for imparting service traverse and gain to the ring-rail that the yarn may be wound on the bobbin with a predetermined filling wind, a slide between the builder motion and ring-rail, a lever pivotally mounted between its ends and movable with the slide, a latch carrier having a latch to engage the lever as the slide is reciprocated for causing the traverse movement 75 and gain to be shortened in the same proportion during the formation of preliminary windings, a cam for holding the latch in position to engage the lever, and means for turning the cam to permit the latch to assume an inoperative position when the preliminary windings are completed.

3. In a machine of the character described, 90 the combination of the ring-rail and builder motion, means between the ring-rail and builder motion for transmitting movements of the latter to the former, a lever carried by said means and having its opposite ends connected to the builder motion, a latch for rocking the lever as it is 95 moved with said means to shorten both the traverse and gain in the same proportion during preliminary windings, a cam for controlling the latch, and means for actuating the cam to permit the latch to move 100 into an inoperative position upon completion of the preliminary windings to cause the full service traverse and gain prescribed by the builder motion to be transmitted at once to the ring-rail.

4. In a machine of the character described, 110 the combination of a ring-rail, a builder arm for imparting to the ring-rail a service traverse and gain that the yarn may be laid upon the bobbins with a predetermined filling wind, a slide between the ring-rail and builder arm, a lever pivoted between its ends to said slide, connections from the builder arm to opposite ends of the lever, latch means acting upon the lever to 115 turn upon its pivot as it moves with the slide in one direction and cause the traverse and gain toward the tip of the bobbin only to be shortened that preliminary windings or a bunch may be laid upon the bobbin 120 while maintaining the unaltered relation of the windings nearer the base of the bobbin, and means for rendering said latch means 125 ineffectual after a predetermined number of preliminary windings have been laid and 130

to cause full service traverse of the ring-rail at once or the completion of the preliminary windings.

5. In a machine for winding yarn on a slotted bobbin, the combination of the ring-rail, a builder motion for imparting to the ring-rail a service traverse and gain that the yarn may be wound upon the bobbin with a predetermined filling wind, means 10 between the ring-rail and builder motion including a slide, a lever pivoted between its ends on said slide, connections between the opposite ends of the lever and the builder motion and a latch to engage the lever as it moves with the slide in one direction for causing preliminary windings to be laid upon the bobbin beyond the slotted portion with the said predetermined filling wind of proportionately shorter traverse and gain, 20 and a cam acting upon the latch for causing the said predetermined filling wind with full service traverse and gain to proceed at once to cover the slot in the bobbin upon completion of the preliminary windings.

25 6. In a machine of the character described, the combination of the ring-rail, a builder arm, a slide between the builder arm and ring-rail, a lever pivoted between its ends to the slide, connections between the 30 builder arm and opposite ends of the lever, means acting repeatedly upon a predetermined point of said lever to cause the traverse and gain toward the tip of the bobbin only to be shortened that the preliminary 35 windings may be laid upon the bobbin while maintaining the unaltered shape of the winding adjacent the base of the bobbins, and devices for controlling the number of repeated actions of said means upon the predetermined point of the lever and for freeing 40 the movement of the slide when the preliminary windings are completed that full service traverse and gain may be at once initiated.

45 7. In a machine of the character described, the combination of a ring-rail, a builder motion for imparting to the ring-rail a service traverse and gain that the yarn may be laid upon the bobbin with a 50 predetermined filling wind, means between the ring-rail and builder motion including a slide, a lever pivoted between its ends to said slide, and connections from the builder motion to opposite ends of the lever for causing the traverse and gain toward the 55 tip of the bobbin only to be shortened that preliminary windings may be laid upon the bobbin while maintaining the unaltered relation of the windings nearer the base of the bobbin, and means for causing service 60 windings with full traverse and gain as prescribed by the builder motion to be laid at once upon completion of the preliminary windings.

65 8. In a machine of the character de-

scribed, the combination of a ring-rail and builder motion, a slide between said ring-rail and builder motion, a quadrant connected directly to the slide to transmit movements of the slide to the ring-rail that the 70 yarn may be laid upon the bobbin with a predetermined filling wind, a lever pivotally mounted between its ends on said slide, connections between the two ends of the lever and builder motion, means for rocking 75 said lever on its fulcrum as the slide is moved during the preliminary windings that the yarn may be laid upon the bobbin with correspondingly short traverse and short gain in one direction and then freeing 80 said lever to bodily movement with the slide that windings may be laid with full traverse and gain of the predetermined filling wind.

9. In a machine of the character de- 85 scribed, the combination of a ring-rail and builder motion, a slide between said ring-rail and builder motion, a quadrant connected directly to the slide to transmit movements of the slide to the ring-rail that the 90 yarn may be laid upon the bobbin with a predetermined filling wind, a lever pivotally mounted between its ends on said slide, connections between the two ends of the lever and builder motion, means for rock- 95 ing said lever on its fulcrum as the slide is moved during the preliminary windings that the yarn may be laid upon the bobbin with correspondingly short traverse and short gain in one direction and then freeing 100 said lever to bodily movement with the slide that windings may be laid with full service traverse and gain of the predetermined filling wind, and means for varying 105 the number of layers of the preliminary windings.

10. In a machine of the character de- 110 scribed, the combination of a ring-rail and builder motion, a lever pivotally connected between its ends to said slide, connections between the ends of said lever and builder motion and between the slide and ring-rail, a latch, means for causing the latch to engage and tilt said lever as the 115 slide moves in one direction to shorten the traverse and gain as the yarn is laid toward the tip of the bobbin during preliminary windings, and thereafter to move said latch to an inoperative position that the 120 yarn may be laid upon the bobbin with full length of service traverse and gain.

11. In a machine of the character de- 125 scribed, the combination of a ring-rail and builder motion, a slide between said ring-rail and builder motion, a lever pivotally connected between its ends to said slide, connections between the ends of said lever and builder motion and between the slide and ring-rail, a latch, means for causing the 130

latch to engage and tilt said lever as the slide moves in one direction to shorten the traverse and gain as the yarn is laid toward the tip of the bobbin during the preliminary 5 windings, and devices for moving said latch to an inoperative position with respect to said lever after a predetermined number of layers have been laid in the preliminary windings that the yarn may then be laid 10 upon the bobbin with full length of service and gain.

12. In a machine of the character described, the combination of a ring-rail and builder motion, a slide, a lever pivotally 15 mounted on the slide, connections between the lever and builder motion and between the slide and ring-rail, a latch carrier having a latch to engage the said lever and tilt it as it is moved with the slide in one direction to thereby shorten the traverse and gain correspondingly in one direction, a cam for controlling the latch carrier and latch, and means for operating the cam as the slide is reciprocated to cause the latch carrier to 20 be moved to an inoperative position with respect to said lever that windings with full service traverse and gain may be laid.

13. In a machine of the character described, the combination of a ring-rail and 30 builder motion, a slide, a lever pivotally mounted on the slide, connections between the lever and builder motion and between the slide and ring-rail, a latch carrier having a latch to engage the said lever and tilt it as it is moved with the slide in one direction to thereby shorten the traverse and gain correspondingly in one direction, a cam for controlling the latch carrier and latch, means for operating the cam as the slide 35 is reciprocated to cause the latch carrier to be moved to an inoperative position with respect to said lever that windings with full

service traverse and gain may be laid, and means for varying the time of action of the cam to vary the number of layers that 45 shall be laid in the preliminary windings.

14. A bunch builder, comprising a slide, a lever pivoted to the slide, a builder motion connected to opposite ends of the lever, means for turning the lever upon its fulcrum for modifying the movement of the slide during preliminary windings, a cam for controlling said means, a ratchet for moving the cam, a pawl for operating the ratchet by movement of the slide, a retaining 50 pawl for said ratchet adapted to be tripped by the said lever after the preliminary windings have been completed, and means for returning the ratchet and cam to initial position when the retaining pawl 55 is tripped.

15. A bunch builder, comprising a slide, a lever pivoted to the slide, a builder motion connected to opposite ends of the lever, means for turning the lever upon its fulcrum for modifying the movement of the slide during preliminary windings, a cam for controlling said means, a ratchet for moving the cam, a pawl for operating the ratchet by movement of the slide, a retaining 60 pawl for said ratchet adapted to be tripped by the said lever after the preliminary windings have been completed, and means for returning the ratchet and cam to initial position when the retaining pawl 65 is tripped, and an adjustable stop for determining the initial position of the ratchet and cam.

In testimony whereof, I have signed my name to this specification, in the presence of two subscribing witnesses.

ALONZO E. RHOADES.
